UNITED STATES PATENT OFFICE.

JAMES MACFARLANE, OF MALDEN, MASSACHUSETTS.

HIGH AND LOW WATER ALARM FOR STEAM-BOILERS.

SPECIFICATION forming part of Letters Patent No. 431,271, dated July 1, 1890.

Application filed March 5, 1890. Serial No. 342,765. (No model.)

To all whom it may concern:

Be it known that I, JAMES MACFARLANE, a citizen of the United States, residing at Malden, in the county of Middlesex and State of Massachusetts, have invented certain new and useful Improvements in High and Low Water Alarms for Steam-Boilers; and I do declare the following to be a full, clear, and exact description of the invention, such as will enable others skilled in the art to which it appertains to make and use the same, reference being had to the accompanying drawings, and to the letters of reference marked thereon, which form a part of his specification.

Figure 1 is a front elevation, partially in section, and Fig. 2 a side view, of a water-gage of ordinary construction, provided with my invention. Fig. 3 is a front view of the frame W, showing the slide X in a raised position.

My invention consists in providing the glass tube of a water-gage, such as are in common use, with an auxiliary or branch tube connected thereto and arranged to stand vertically, or about so, and parallel to the main glass tube, so that the water in both tubes will stand at the same level with that in the boiler, and in said branch tube is arranged a float adapted to rise and fall with the water, a rod attached to said float extending up through the cap, which closes the top of said branch tube, and projecting from the upper part of said rod are prongs adapted to operate with the poles of two electric circuits for the purpose of sounding two bells in each circuit, one bell of each circuit being located in the boiler-room, the other bell in each of the said circuits being in the office of the works, the object of such arrangement being to indicate simultaneously in the boiler-room and in the said office when the water in the boiler is too high or too low, as the case may be.

In the drawings, A denotes the upright glass tube of a water-gage, which communicates at its ends with the water and steam of the boiler through elbows B and C. The passages in said elbows which communicate with the boiler are closed by plugs D and E, which connect with the elbows by screws and are operated by handles or wheels H I in the usual manner.

In carrying out my invention I provide the tube A with an auxiliary or branch tube K, which may be integral therewith or may be united thereto by a connection, the longer portion of said tube being parallel to the tube A, and near its top it is supported by a band or connection L, secured to it and to the tube A. Within the tube K is arranged a float M, which rests on the water therein and is raised and lowered by the rise and fall of the water in the boiler, the water in said tube standing on a level with that in the boiler. A rod N of small diameter extends from the float upward through the cap O, which closes the mouth of the tube K, said rod being provided with prongs P and Q, the prong P operating with the poles a b of the circuit R, which connects the bells Y and Z, indicating "high water," and the prong Q operates with the poles c d of the circuit S, which connects the bells A' and B', indicating "low water."

T represents the battery.

The poles a b and c d are constructed of thin flexible metal and are fixed to and project from an insulator e, supported by an arm f, secured to the upper elbow B, or the said insulator may be secured directly to the boiler. A tri-armed lever U, made of insulating material and fulcrumed to said insulator e, is arranged with the poles a b and c d of the two circuits that it can be operated to force said poles apart and break the closed circuit when it is desired to stop the ringing of the bells of either circuit after the alarm has been given. A spring V, connected to one of the arms of said lever and to the boiler, operates to keep the wedge-shaped ends o and p of the said lever from entering between the poles of the circuits. A cord or wire s, connected to the arm r of said lever U, is provided at its lower end with a ring t.

Fixed to the boiler-front or arranged in any convenient place in the boiler-room is a frame W, in which is arranged a slide X, provided with a headed stud u.

In Fig. 1 of the drawings the prong P of the float-rod is shown as nearly against the pole b, and we will suppose the water in the boiler to be rising. As the said prong ascends, it will move the end of pole b upward against the pole a and close the circuit R; hence the high-

water bells Y and Z will sound an alarm. The bell Y we will suppose to be located in the boiler-room and the bell Z in the office. Should the attendant in charge of the boiler 5 desire to stop the ringing of the bells before the water in the boiler subsides enough to cause the breaking of said circuit, he seizes the ring *t* and depresses it, and at the same time raising the slide X, passes the said ring 10 over the stud *u* in the slide, which holds the said slide raised and exposes to view the word "danger." In depressing the ring *t* the wedge-shaped end *p* of the lever U will enter between the poles *a* and *b* and force them 15 apart, thus breaking the circuit R and stopping the alarm; but the slide X cannot be set free from the ring *t* to cover the word "danger" without the ringing of the bells Y and Z until the water in the boiler has lowered sufficiently 20 to depress the float and its prong P enough to allow of the separation of the pole *b* from the pole *a*. In case of low water in the boiler the prong Q of the float-rod N depresses the pole *c* into contact with the pole *d*, which closes the 25 circuit S and rings the low-water bells A' and B', and the attendant has recourse to the slide X, as before, if he wishes to stop the sounding of the alarm before the water rises in the boiler sufficient to break the said circuit; but either 30 the said bells must ring or the word "danger" be exposed to view until the water in the boiler rises enough to lift the float and carry its prong Q upward and allow the pole *c* to move away from the pole *d* and break said circuit.

35 The object in providing each circuit with two bells is to make sure that some one besides the attendant in the boiler-room shall be made aware of the fact that danger exists which requires immediate attention, and in case the 40 bell sounding an alarm in the office ceases to

ring shortly after the alarm is given it will show to those in the office that some one in the boiler-room is apprised of the danger and is attending to the matter; but should the bell in the office continue to ring some one in said office would investigate to ascertain why the matter was not receiving attention. Thus it will be seen that by my improvement additional protection against accidents caused by too high or too low water in the boiler will 45 result.

What I claim is—

1. The water-gage tube provided with the branch tube, the float arranged in the latter, and the rod fixed to said float, provided with 55 prongs and adapted to slide in the cap of the branch tube, as explained, combined with the poles of the electric circuits arranged with said prongs, essentially as represented.

2. The combination of the electric circuits 60 R and S, having one or more bells in each, the poles of said circuits formed of flexible metal springs, arranged as shown, the insulator supporting said poles, the tri-armed lever fulcrumed to said insulator and having to two of 65 its arms wedge-shaped ends, the spring connected to said lever, the cord or wire connected thereto, the frame W, and the slide X, provided with headed stud adapted to slide in said frame, with the water-gage provided 70 with the branch tube K, cap O, float M, and rod N, fixed thereto, and provided with prongs to operate with the poles of the said circuits, all substantially as explained.

In testimony whereof I affix my signature in 75 presence of two witnesses.

JAMES MACFARLANE.
